INTERFOLDED TISSUE DISPENSER

Wilfred H. West, Berkeley, Calif., assignor to
Crown Zellerbach Corporation, San Francisco,
Calif., a corporation of California

Application July 24, 1939, Serial No. 286,208

4 Claims. (Cl. 312—60)

This invention relates to a cabinet for the dispensing of interfolded sheets of tissue paper.

The object of the present invention is to generally improve and simplify the construction and operation of dispensing cabinets of the character described; to provide a dispensing cabinet which may be refilled from time to time with a minimum of effort and which provides free access for placing stacks of tissue therein without danger of waste by spilling; to provide a dispensing cabinet having a slotted bottom for the support of the tissue, said bottom sloping upwardly toward the front of the cabinet so that the slot and the sheet of tissue projecting therefrom are brought into full view and are readily accessible for removal of the sheets of tissue; to provide a cabinet having a bottom sloping upwardly and toward the front together with a rear curved plate which causes the lower portion of the stack of tissue to curve forward and assume the same plane as the inclined bottom; to provide a bottom having a dispensing slot or opening formed therein, the ends of said slot being extended vertically and enlarged to expose the ends of the lowermost sheets of tissue whereby said ends may be grasped and pulled out of the slot to start feeding the tissue, the purpose being to eliminate interleaving of a stack of tissue when a new supply is placed in the cabinet; and further to provide a dispensing bottom panel having a roughened area on a portion of its inner surface to frictionally retain the lowermost sheet of a stack of tissue when the projecting sheet interleaved therewith is being withdrawn.

35 The cabinet is shown by way of illustration in the accompanying drawing, in which

Fig. 1 is a perspective view of the same;

Fig. 2 is a central vertical section of Fig. 1 showing the cabinet applied to the wall or similar support; and

Fig. 3 is a cross section taken on line III—III of Fig. 2.

Referring to the drawing in detail, 2 indicates the back wall of a cabinet, 3—3 a pair of side walls, 4 a partial top, 5 a bottom supporting panel in which is formed a dispensing slot 6, and 7 indicates a cover hinged as at 8 to the top section 4. The back portion 2, together with the sides 3—3, the top 4, and the bottom 5 are permanently secured or formed integral with relation to each other. This leaves the cover 7 as the only movable part, this being possible as it is hinged to the top as at 8 and may be swung about the hinges from the closed or full line position shown

in Fig. 2 to the open position shown in dotted lines at 1a.

The cabinet is intended for the reception and dispensing of toilet tissue of the interfolded type, and the purpose of the invention is to simplify the operation of refilling the cabinet and to render the tissue more accessible and easily removable when it is to be dispensed.

By referring to Figs. 1 and 2, it will be noted that the slotted bottom slopes upwardly toward the front of the cabinet and that a curved back plate 9 is provided with functions to direct and curve the lower portion of a stack of tissue toward the user. This, together with the sloping bottom, brings the sheet to be dispensed into full view and into a position where it is readily grasped or withdrawn. In an ordinary cabinet, during humid weather or when static electricity is in the air, the projecting sheet often hugs the wall. In this cabinet the sloping bottom brings the slot away from the wall and into full view. Hence the projecting sheet is not only in full view and readily reachable but is far enough away from the wall to obviate one touching anything but the tissue sheets that are to be withdrawn. The bottom of the package or stack of interfolded toilet tissue when inserted in this cabinet assumes a wedge shape at the front and a round or curved portion at the back, so as to conform to the plane presented by the sloping bottom. From that position the pull on the projecting sheet is up and towards the user instead of down and away. This makes for greater convenience in withdrawing the paper and insures a more positive and even pulling action. By referring to Fig. 2, it will be noted that the upper portion of the bottom section 5 is roughened or corrugated as indicated at 10. The cooperating curved back plate 9, together with the corrugations in front of the slot 6, prevent a number of sheets from being pulled out at one time. Friction in the slot 6 is compensated when the cabinet is fully loaded and at the same time, as the supply diminishes, the friction produced by the corrugations diminishes the tendency for several sheets to be pulled out when one is being withdrawn.

In Figs. 1 and 2 it will be noted that the cover 7 is curved as at 1b adjacent its upper end. This permits the cover when opened, as shown in dotted lines (see Fig. 2) to rest flat against the wall without straining the hinges. Also it increases the size of the opening and permits free access for placing in the cabinet a fresh supply of tissue without hindrance. The hands of the janitor

or person filling the cabinet are at the same time free to handle the tissue, which is a decided advantage as it is more convenient and minimizes the possibility of waste by spilling.

5 The free feeding of a stack of tissue when placed in the cabinet towards the sloped bottom is accomplished by the curved plate 9 extending from the lower back part of the cabinet to the dispensing panel in an arc that maintains the approximate dimension of the folded sheets. Thus the lower portion of the stack assumes a wedge shape and curves forward to the same plane as the sloping bottom or dispensing panel. The tissue then easily dispenses up and towards the 10 user instead of down and away as is common in ordinary cabinets.

Ordinary cabinets require the interleaving of the last sheet of the remaining supply with the first sheet of a new supply. This cabinet eliminates this awkward and inefficient operation. This is due to the fact that the lateral extremities of the dispensing slot 6 are widened and extended upwardly into the sides 3 to form open portions such as indicated at 6a. With this addition or extension of the dispensing slot 6, it becomes unnecessary to interleave the new supply because when a break in interleaving occurs, the lower ends of the interfolded tissue will be exposed and uncovered by the enlarged extensions of the 20 slot indicated at 6a, thus permitting them to be grasped by the fingernails or some suitable instrument to start a new supply of interleaved sheets. This is a decided advantage to the janitor who fills these cabinets and a great convenience to the user when breaks in interleaving of tissue occur. The corrugated or roughened surface 10 previously referred to does not only frictionally resist withdrawal of all sheets except the sheet to be dispensed, but it also prevents the first few sheets from dropping down the inner face of the sloping bottom, as the corrugations engage such sheets and act as a retarder for them. The ridges also offset the friction between sheets 25 when a sheet is being withdrawn.

45 Summarizing statements heretofore made, it may be said that the cabinet is particularly designed to permit easy access in filling. Also it gives greater capacity when the door is open, as it is out of the way and allows complete access to the cabinet interior. The tissue is placed in the body of the cabinet rather than in an open frame. This minimizes spilling and permits use of the entire cabinet for filling. This last feature is not common in conventional cabinets as space must be afforded to permit entrance of the hand or hands to permit interleaving of sheets of the old and the new supply. The inner face of the cover is provided with ribs extending from the top to the bottom thereof as shown at 1c. These ribs 50 are placed on the opposite sides (see Figs. 2 and 3) and form guides or trackways to guide a stack of tissue from the top to the bottom of the cabinet, thereby lessening friction on the ends of the tissue stack. The cabinet as constructed lends 55 itself to molding from any one of a number of different types of plastic material. This permits different color effects to be used and surface ornamentation of different character. The curved top presented by the cabinet minimizes its use 60 as a parking place for burning cigars and cigarettes. Wiping the cabinet with a soft cloth is all that is necessary to keep it clean. With the use of plastic material in its construction the luster is permanent, as such a finish is inherent 65 in most of the molded plastic compounds. Clean-

liness, sanitation, and a permanent pleasing appearance are therefore characteristics of the cabinet besides the many other advantages specified.

The back wall of the cabinet is perforated or slotted to receive screws or similar fastening means, thereby simplifying the operation of securing the cabinet as a whole to a wall surface or any other suitable support.

While certain features of my invention have been more or less specifically described and illustrated, I wish it understood that various changes may be resorted to within the scope of the appended claims, and that the materials and finish may be such as the experience of the manufacturer may dictate and other conditions demand.

Having thus described my invention, what I claim and desire to secure by Letters Patent is—

1. A device of the character described comprising a cabinet for the reception of a vertically disposed stack of interfolded sheets of tissue paper, a bottom section in the cabinet to support the stack of tissue, a sheet dispensing slot formed in the bottom and extending from side to side of the cabinet, said bottom sloping upwardly towards the front of the cabinet to bring the dispensing slot and sheets dispensed therethrough into full view, an enlarged slot formed in each side of the cabinet and in communication with the bottom slot, said enlarged slots exposing the opposite ends of the lowermost layers of interfolded sheets to permit said sheets to be grasped and pulled down through the bottom slot to start feeding of the interfolded sheets through the bottom slot, and a curved plate at the rear of the cabinet and at the lower end thereof to curve 25 and direct the lower portion of the tissue stack forwardly into the plane of the bottom section and the dispensing slot formed therein.

2. A device of the character described comprising a cabinet for the reception of a vertically 40 disposed stack of interfolded sheets of tissue paper, a bottom section in the cabinet to support the stack of tissue, a sheet dispensing slot formed in the bottom and extending from side to side of the cabinet, said bottom sloping upwardly to- 45 wards the front of the cabinet to bring the dispensing slot and sheets dispensed therethrough into full view, an enlarged slot formed in each side of the cabinet and in communication with the bottom slot, said enlarged slots exposing the 50 opposite ends of the lowermost layers of interfolded sheets to permit said sheets to be grasped and pulled down through the bottom slot to start feeding of the interfolded sheets through the bottom slot, and means adjacent the slot and in front 55 thereof for frictionally engaging the lower surface of the lowermost sheet in the tissue stack to retain it against removal when an interleaved sheet is being withdrawn through the slot.

3. A device of the character described comprising a cabinet for the reception of a vertically disposed stack of interfolded sheets of tissue paper, a bottom section in the cabinet to support the stack of tissue, a sheet dispensing slot formed in the bottom and extending from side to side of 65 the cabinet, said bottom sloping upwardly towards the front of the cabinet to bring the dispensing slot and sheets dispensed therethrough into full view, an enlarged slot formed in each side of the cabinet and in communication with the bottom 70 slot, said enlarged slots exposing the opposite ends of the lowermost layers of interfolded sheets to permit said sheets to be grasped and pulled down through the bottom slot to start feeding of the interfolded sheets through the bottom slot, and 75

a roughened area formed on the inner face of the bottom section forwardly of the slot for frictionally engaging the lower surface of the lowermost sheet in the tissue stack to retain it against removal when an interleaved sheet is being withdrawn through the slot.

4. A device of the character described comprising a cabinet for the reception of a vertically disposed stack of interfolded sheets of tissue paper, a bottom section in the cabinet to support the stack of tissue, a sheet dispensing slot formed in the bottom and extending from side to side of the cabinet, said bottom sloping upwardly towards the front of the cabinet to bring the dispensing slot and sheets dispensed therethrough into full view, an enlarged slot formed in each side of the cabinet and in communication with the bottom slot, said enlarged slots expos-

ing the opposite ends of the lowermost layers of interfolded sheets to permit said sheets to be grasped and pulled down through the bottom slot to start feeding of the interfolded sheets through the bottom slot, a curved plate at the rear of the cabinet and at the lower end thereof to curve and direct the lower portion of the tissue stack forwardly into the plane of the bottom section and the dispensing slot formed therein, a cover member hinged to the top of the cabinet, 10 said cover closing a portion of the upper end of the cabinet and the front of the cabinet, and extending downwardly substantially to the sloping bottom section, and a pair of ribs on the inner face of the cover, one on each side thereof, to 15 form a vertical guideway for the stack of tissue placed within the cabinet.
